UNITED STATES PATENT OFFICE.

PHILIP MUELLER AND ANTON C. SCHUERMANN, OF DECATUR, ILLINOIS, ASSIGNORS
TO ADOLPH MUELLER, TRUSTEE, OF DECATUR, ILLINOIS.

SUPPLY VALVE FOR DRINKING FOUNTAINS.

Original application filed November 12, 1919, Serial No. 337,490. Divided and this application filed October 15, 1923. Serial No. 668,635.

To all whom it may concern:

Be it known that PHILIP MUELLER and ANTON C. SCHUERMANN, citizens of the United States, residing at Decatur, in the county of Macon and State of Illinois, have invented new and useful Improvements in Supply Valves for Drinking Fountains, of which the following is a specification.

The present invention relates to a supply valve and operating mechanism therefor, which is particularly adapted for use with drinking fountains of the pedestal type, a preferred form of which, is set forth in applicants' copending application, Serial No. 337,490, filed November 12, 1919, (Patent No. 1,490,677, Apr. 15, 1924), of which this case is a division made under official requirement.

Primarily, the invention consists in providing a valve body with an adjustable valve operating mechanism so disposed as to be readily accessible for the purpose of necessary adjustment to the valve and its associated parts. The operation of the valve is effected by a pedal disposed outside of the valve housing, and so arranged upon depression thereof, to move the valve from its seat, thus permitting the water to pass from the supply pipe through the cock body.

In order that the valve may be operated by children as well as adults, a lever means is provided for actuating the valve from any desired level.

A further advantage of the present development resides in disposing within the valve body, a regulator and stop mechanism arranged opposite the valve opening so that the supply may be controlled or entirely stopped as may be deemed necessary.

In the drawings herewith, we have illustrated one embodiment of our invention:

Figure 1 is a sectional view of a fountain disclosing our invention,

Figure 2 is a detail sectional view of the supply valve operating lever and regulator screw,

Figure 3 is an end elevation partly in section of the supply valve, showing one form of hand hole cover,

Figure 4 is a modified form of the supply valve.

Referring to the drawings wherein like numerals designate like parts in the vari-

ous figures, 10 denotes the pedestal of a drinking fountain, which forms a housing 55 for the base plate 11, through which extend the supply nipple section 12 and the waste pipe section 13. The nipple 12 is connected to the cock body 14 which in turn is secured to the supply pipe section 15 by a slip joint 60 union 16.

The supply pipe section 17, which leads to the bubbler head (not shown) is vertically disposed within the offset waste 18 and is connected to the supply section 15 by an 65 elbow coupling 19.

A valve stem 20 longitudinally disposed within the cock body 14, is formed at its inner end with a shouldered recess portion, to which is threadedly secured, by the screw 70 21, the seat washer 22. A closure cap 23, threadedly secured to the cock body 14, is so formed as to provide a shoulder for the spring 24, which surrounds the stem 20, and normally tends to force the washer 22 into 75 the valve seat 25.

A diametrically disposed pin 26 secured to the valve stem 20, is adapted to engage corresponding slots arranged in the interior wall of the cap 23 so as to prevent relative 80 rotation of the valve stem with respect to the cap.

A stuffing nut 27 through which the valve stem 20 passes is threaded to the cap 23 and maintained in tight connection 85 therewith by the packing 28. The stuffing nut 27 is preferably held against accidental displacement by the lock finger 29 which engages the hexagonal periphery of the said nut.

To the outer end of the valve stem 20 is adjustably secured, preferably by the screw threaded connection shown, a sleeve 30 provided with radially protruding spaced apart collars or flanges 31. The sleeve 30 is provided at its outer end with a slot 32 adapted to engage a cotter pin 33 extending through an opening in the stem 20, so that when the sleeve has been adjusted longitudinally of the stem, it is locked by the pin 33 against 100 accidental rotation.

To the underside of the cock body 14 is attached an arm 34, to the free end of which is pivotally secured by the pin 35, the arms 36 of a forked pedal lever 37, having its outer extremity terminating in a pedal 38,

The inner end of the lever 37 is provided with outwardly extending lugs 39 adapted to be engaged between the flanges 31.

It will be apparent that upon the application of the foot to the pedal extremity 38 and the pedal lever being rocked on its pivot 35, the lugs 39 connected with the adjustable sleeve 30 will cause the valve 22 to be removed from its seat, at the same time compressing the spring 34, and thus permit water to pass from the supply pipe through the cock body to any suitable source of supply. It will be observed that upon release of the pedal, the valve will be automatically shut off by the expansion of the spring 24.

In order that the supply may be regulated or entirely cut off, if necessary, there is provided a regulator screw or stop 40 threaded to the interior portion of the cock body 14, on the opposite side of the valve seat and in direct alignment with the valve stem. A packing 41 and gland 42 are arranged within the body of the cock and secured thereto by the adjustable nut 43. The outer end of the screw 40 is formed so as to receive a wrench or other suitable tool to permit adjustment of the regulator. In order to prevent accidental displacement of the screw 40, a stop finger 44 similar to the stop 29 previously described, is provided so as to engage the serrated portion 45 of the stop screw.

In order to provide an installation which may be used by children as well as adults, without the necessity of changing the essential parts of the operating mechanism, we provide a second valve operating pedal 46 formed with arms 47 which are adapted to be pivotally engaged to the cock body 14 by the pin 48. The arms 47 further provide a lifting toe which contacts with a projection 49 on the adult's pedal 36. The outer end of the child's pedal 46 extends through a slot 50 in the lower portion of the pedestal 10 and is pivotally connected to a push rod 51 which is operatively connected at its upper end to the floor of a child's stand (not shown).

It will be seen that upon depressing the outer end of the child's pedal 46, the arms 47 will lift the projections 49 of the adult's pedal 36, and operate the valve exactly as it is operated when the adult's pedal is depressed. It is, of course, apparent that no operation of the child's pedal is accomplished when the adult's pedal is manipulated.

In order to provide ready access to the cock body and to permit adjustment of the stop and regulator to the valve and pedal parts, a cover plate 53 is arranged to cover the circular opening 54 in the wall of the pedestal and is removably secured thereto by the cross bar 55 and the threaded nut 56, provided at its forward end with a hex-

agonal head as shown. It will be observed that the regulator screw 40 is in line with the hand hole screw 56 and preferably we provide a single wrench for rotating both the regulator screw 40 and the screw 56 of the cover plate, thus obviating the necessity of providing different wrenches for manipulating these two parts.

In the form of the invention disclosed in Figure 3, a similar construction to that heretofore described is shown, except that no provision is made for the child's operating pedal, it being designed to have only the adult's operating lever 57, and a different type of cover plate than that disclosed in Figure 1, the cover plate being of the form of a box 58, the lower end of which is provided with lugs 59 which rest upon the pedestal with the upper part of the housing conforming to the pedestal wall, and enclosing the recess 60 in the pedestal wall, through which the stop and regulator portions of the cock body extends. The cover plate 58 is anchored in place by means of the clamping bar 61, the inner end of which is bent as shown to engage the wall of the pedestal and the outer end is arranged to be seated in a box 62 formed by ribs on the inner side of the cover plate. A clamping screw 63 extends through the top of the cover plate and threadedly engages the clamping bar 61, so that when the cover plate or housing has been set in position and the clamping bar drawn up by means of the screw, the housing 58 will be locked firmly in place. With this arrangement, the cock body and its associated parts are very readily accessible for adjustment and repairs.

The stop and regulator disclosed in Figure 4 are slightly varied in construction from that heretofore described. This construction comprises the long screw 64 having a threaded engagement of suitable length with the cock body and being arranged opposite the valve seat. The screw 64 is provided with a head 65 adapted to be engaged by a screw locking pawl 66 pivoted on the cock body so that when the screw has been adjusted the pawl may be dropped into locking engagement so as to prevent accidental rotation and eliminate all possibility of disarranging the regulated supply. The stop regulators thus described are entirely enclosed by means of a cap 66 which is threaded to the exterior portion of the cock body, as shown and which is of wrench formation so that it may be turned by hand or a suitable tool after the cover plate has been removed.

It is to be understood that this disclosure is merely illustrative of several preferred embodiments of our invention, and that such changes in design and substitution of mechanical equivalents for the various expedi-

ents disclosed, may be made without departing from the spirit of the invention and the scope of what is claimed.

We claim:

5. 1. A supply valve for drinking fountains comprising a valve body, a normally spring-closed valve in said body, a forked valve operating lever pivoted on said body, an adjustable winged nut on the valve stem 65
10 gaging said forked lever, and a second valve operating lever pivoted on said body and engaging said first-mentioned lever.
2. A supply valve for drinking fountains comprising a valve body, a normally spring-closed valve in said body, a forked valve operating lever pivoted on said body, an adjustable winged nut on the valve stem 70
15 gaging said forked lever, and a second valve operating lever pivoted on said body and engaging said forked lever, and a second valve 75
20 operating lever pivoted on said body and engaging said first-mentioned lever, said first-mentioned lever adapted to actuate the valve independently of the second lever.
3. A supply valve for drinking fountains comprising a valve body, a normally spring-closed valve therein, a forked valve-operating lever pivoted on said body, an adjustable winged nut on the valve stem 80
25 gaging said forked lever, and a second forked lever straddling said valve body and pivoted thereto to engage said first-mentioned lever for operating the valve.
4. A supply valve for drinking fountains comprising a valve body, a normally spring-closed valve therein, a forked valve-operating 85
30 lever pivoted on said body, an adjustable winged nut on the valve stem engaging said forked lever, and a second forked lever straddling said valve body and pivoted thereto to engage said first-mentioned lever 90
35 for operating the valve, said second lever adapted to operate the valve from a higher level than the said first lever.
5. A supply valve for drinking fountains comprising a valve body, a cap provided 95
40 with an internal recess attached to said body, a stuffing nut secured to said cap, means for locking said nut in position, a normally spring-closed valve in said body having its stem member projecting through said cap
45 and nut, a sleeve provided with spaced apart shoulders adjustably secured to said stem, an operating lever pivoted on said valve body, and having upwardly extending lugs 100
50 adapted to fit between said spaced apart shoulders, for actuating said valve.
6. A supply valve for drinking fountains comprising a valve body, a cap secured to said body, a normally spring-closed valve in said body having its stem member projecting 105
55 through said cap, means on said cap to pre-
vent relative rotation of said stem, an operating lever pivoted on said valve body, and an adjustable connection between said operating lever and the valve stem.
7. A supply valve for drinking fountains 65 comprising a valve body having laterally disposed arms on the inlet and outlet sides respectively of the valve body and connected together by a restricted opening, a cap having a reduced portion secured to one of said arms, a normally spring-closed valve for closing said opening, having its stem projecting through said cap, an adjustable sleeve on said stem adapted to be engaged by an operating member for actuating said valve, a cap secured to the other of said arms, a regulator and stop projecting through said cap, and means for locking said regulator and stop in adjusted position.
8. A supply valve for drinking fountains 75 comprising a valve body having laterally disposed arms on the inlet and outlet sides respectively of the valve body and connected together by a restricted opening, a cap having a reduced portion secured to one of said arms, a normally spring-closed valve for closing said opening, having its stem projecting through said cap, an adjustable sleeve on said stem adapted to be engaged by an operating member for actuating said 80 valve, a cap secured to the other of said arms, a regulator and stop projecting through said cap, means for locking said regulator and stop in adjusted position and a covering cap for said locking means and regulator.
9. A supply valve for drinking fountains 85 comprising a valve body, a normally spring-closed valve therein, means for operating said valve, a regulator and stop opposite said valve, means for locking said regulator and stop in adjusted position, and a covering cap for said regular locking means.
10. A supply valve for drinking fountains 90 comprising a valve body, a normally spring-closed valve, an adjustable sleeve on the valve stem, means for operating said sleeve and means for independently operating said means from opposite sides of the valve body.
11. A supply valve for drinking fountains 100 comprising a valve body, a normally spring-closed valve therein, adjustable means for operating said valve, a regulator and stop opposite said valve, means on said valve body for locking said regulator and stop in adjusted position, and a cover cap enclosing 105
110 said regulator and locking means.
- In testimony whereof we have hereunto set our hands.
- PHILIP MUELLER.
ANTON C. SCHUERMANN.
